UNITED STATES PATENT OFFICE.

FRANCIS A. WINSLOW, OF CHICAGO, ILLINOIS, ASSIGNOR TO THE WINSLOW BROS. COMPANY, OF CHICAGO, ILLINOIS, A CORPORATION OF ILLINOIS.

FIREPROOF STAIRWAY.

SPECIFICATION forming part of Letters Patent No. 747,825, dated December 22, 1903.

Application filed October 28, 1903, Serial No. 178,816. (No model.)

To all whom it may concern:

Be it known that I, FRANCIS A. WINSLOW, a citizen of the United States of America, residing at Chicago, in the county of Cook and 5 State of Illinois, have invented certain new and useful Improvements in Fireproof Stairways, of which the following is a specification.

My invention relates to certain new and 10 useful improvements in fireproof stairways; and its object is to produce a device of this class which shall be simple, comparatively cheap in construction, thoroughly fireproof, and which shall lend itself readily to 15 ornamentation of various sorts.

To these ends my invention consists in certain novel features of construction, which are clearly illustrated in the accompanying drawings, and described in the course of this 20 specification.

In the aforesaid drawings, Figure 1 is a longitudinal section through the center of one of the steps of my improved stairway, the concrete filling being omitted to show construction, the line of section being indicated 25 by the line 1 1 of Fig. 4. Fig. 2 is a longitudinal section in the line 2 2 of Fig. 4 on a smaller scale than Fig. 1 and showing the entire stairway. Fig. 3 is a horizontal section in the line 3 3 of Fig. 1; and Fig. 4 is a vertical transverse section in the line 4 4 of Fig. 2, the concrete filling being removed to show the metal construction.

Referring to the drawings, A A indicate 35 two suitable side plates which are supported in any desirable way at their two ends. These side plates are provided along their lower edges with inwardly-projecting flanges a, Fig. 4. A soffit B, consisting of a flat plate of metal 40 of the width of the stairway, is bolted or otherwise secured to the inwardly-projecting flanges a of the side plates and supported thereby, and the two ends of this soffit are suitably secured to the edges of the floors at the 45 ends of the stairway. Risers C are secured to the soffit by bolts or rivets passing through the soffit and through suitable diagonally-bent or curved flanges c upon each riser. The side plates A are provided with inwardly-projecting lugs a', which are suitably spaced 50 to receive bolts or rivets which pass through

the ends of the risers, as shown in Fig. 3. In this way the risers are secured to the soffit at their lower edge and to the side plates at their ends. A short distance from the top 55 of each riser is a backwardly-projecting lug c', to which is bolted or riveted a brace D, which extends backward to the soffit and is bolted or riveted thereto a short distance below the attachment of the next riser upward. 60 When the stairway has been completed to this point, the space behind each riser is filled with cement or other fireproof material to the level of the braces D. The upper portion of the steps is then filled with a finer grade of 65 cement or composition suitable for forming a fireproof tread, or in the alternative a slab of stone or any desired tread-forming substance is used. Two forms of tread are shown in Fig. 2, the two lower steps being composition treads and the two upper steps being 70 stone treads. In this latter case it will be noted the upper edge of the riser is cut off, so that the tread projects out over the riser instead of abutting against the rear edge 75 thereof.

It will be seen that this stairway is very simple and its fireproof quality is evident. Furthermore, its surfaces are almost entirely flat surfaces of considerable extent, so that 80 any desirable scheme of ornamentation can be adopted. This is especially true of the soffit, which occupies the entire lower side of the stairway and can be made the basis for a large amount of ornamental work. 85

I realize that considerable variation is possible in the details of this construction without departing from the spirit of the invention, and I therefore do not intend to limit myself to the specific form herein shown and 90 described.

I claim as new and desire to secure by Letters Patent—

1. In a device of the class described, the combination with suitable side plates supported at their upper and lower ends, of a substantially flat soffit secured to the lower edges of the side plates, a plurality of risers secured at their lower edges to the soffit and at their ends to the side plate, and a body of 95 fireproof plastic material in the spaces behind the risers. 100

2. In a device of the class described, the combination with suitable side plates, of a substantially flat soffit secured to the lower edges thereof, a plurality of risers secured at 5 their lower edges to the soffit and at their ends to the side plates, a body of fireproof plastic material in the steps behind each riser, and a suitable tread, covering each body of plastic material.
- 10 3. In a device of the class described, the combination with suitable side plates, of a substantially flat soffit secured to the lower edges of the side plates, a plurality of risers secured at their lower edges to the soffit, and 15 at their ends to the side plates, a suitable brace connecting each riser near its upper end with the soffit, and a body of plastic fire-proof material in the steps behind each riser.
4. In a device of the class described, the 20 combination with suitable side plates having inwardly-projecting flanges at their lower edges, of a substantially flat soffit bolted to the flanges, inwardly-projecting lugs on the side plates, suitable risers secured to the so- 25 fit at their lower edges and secured to the
- inwardly-projecting lugs on the side plates at their ends, and suitable fireproof material in the steps behind each riser.
5. In a device of the class described, the combination with suitable side plates having 30 inwardly-projecting flanges at their lower edges, of a substantially flat soffit secured to the flanges on the side plate, suitable risers secured at their lower edges to the soffit, inwardly-projecting lugs on the side plates, 35 means for securing the risers at their ends to the inwardly-projecting lugs on the side plates, rearwardly-extending lugs on the risers, and braces secured at one end to the lugs on the risers and at their other ends to 40 the soffit.

In witness whereof I have signed the above application for Letters Patent, at Chicago, in the county of Cook and State of Illinois, this 23d day of October, A. D. 1903.

FRANCIS A. WINSLOW.
